(57) **CLAIM**

The ornamental design for a nursing bed as shown and described.

DESCRIPTION

FIG. 1 is a front and top perspective view showing a nursing bed of the new design;

FIG. 2 is a rear and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of character reference 9 in FIG. 1;

FIG. 10 is an enlarged view of character reference 10 in FIG. 1;

FIG. 11 is an enlarged view of character reference 11 in FIG. 2;

FIG. 12 is an enlarged view of character reference 12 in FIG. 2;

FIG. 13 is an enlarged view of character reference 13 in FIG. 5;

FIG. 14 is an enlarged view of character reference 14 in FIG. 6;

FIG. 15 is an enlarged view of character reference 15 in FIG. 7;

FIG. 16 is an enlarged view of character reference 16 in FIG. 7;

FIG. 17 is an enlarged view of character reference 17 in FIG. 7; and,

FIG. 18 is an enlarged view of character reference 18 in FIG. 8.

The broken lines depict portions of the nursing bed that form no part of the claimed design.

1 Claim, 18 Drawing Sheets
